UNITED STATES PATENT OFFICE.

JOHN ERVIN PECKENPAUGH, OF FRANKLIN, TEXAS.

WIRE-CLAMP.

1,103,157.

Specification of Letters Patent. Patented July 14, 1914.

Application filed October 6, 1913. Serial No. 793,714.

To all whom it may concern:

Be it known that I, JOHN E. PECKENPAUGH, a citizen of the United States, residing at Franklin, in the county of Robertson 5 and State of Texas, have invented certain new and useful Improvements in Wire-Clamps, of which the following is a specification, reference being had to the accompanying drawings.

10 This invention relates to certain improvements in wire clamps and has relation more particularly to a device of this general character especially designed and adapted for use in connection with a fence produced 15 from a woven wire fabric and the object of the invention is to provide a device of this general character having means of a novel and improved character whereby a convenient and effective clamping engagement 20 may be created with the several longitudinal strands of the wire.

The invention consists in the details of construction and in the combination and arrangement of the several parts whereby 25 certain important advantages are attained and the device is rendered simpler, less expensive and otherwise more convenient and advantageous for use, all as will be herein after more fully set forth.

30 The novel features of the invention will be carefully defined in the appended claim.

In order that my invention may be the better understood, I will now proceed to describe the same with reference to the accompanying drawings, wherein—

Figure 1 is a view in side elevation of a wire clamp constructed in accordance with my invention, and shown in applied position, a part thereof being broken away; Fig. 40 2 is a view partly in end elevation and partly in section illustrating certain details of the invention as herein contained; and Fig. 3 is a fragmentary view in elevation illustrating a further detail of the invention, as herein embodied.

As disclosed in the accompanying drawings, 1 denotes an elongated member preferably formed of steel although I do not wish to be understood as limiting myself 50 to any particular kind of material. This member 1 is adapted to be disposed longitudinally of the woven fabric adapted to constitute a part of the fence, and suitably affixed thereto at proper intervals are the 55 plates 2 substantially L-shaped in cross section and through which are adapted to be

projected the longitudinal strands 3 of the fabric. While these plates may be secured to the body 1 in any desired manner, I prefer that one of the stems be caused to 60 contact with a face of such member 1 and having directed therethrough the anchoring members 4 adapted to suitably engage such member 1, such anchoring means being preferably in the nature of bolts.

65 Pivotedly supported by a stem of each of the plates 2, and preferably the inner or attached stem, is mounted the cam 5 adapted to be swung relatively to the base of the plate 2 and to clamp the wire 3 which may 70 be positioned within said plate, it being understood that the cam 5 is of a thickness less than the space or distance between the stems of the plate 2, in order that the wire strand 3 may be readily and conveniently 75 positioned within the plate beneath the cam. Each of the cams is provided with a forwardly extended arm or projection, which are disposed in the same plane and have their outer ends pivotally attached, as at 80 6, to the rod or bar 7 whereby it will be seen that upon endwise movement being imparted to the bar or rod 7 that the several cams 5 may be adjusted into or out of clamping engagement.

85 In order to effectually manipulate the rod or bar 7, I provide the lever 8 pivotally connected to the member 1 at substantially its longitudinal center, said lever being also pivotally connected at 9, with the bar or rod 90 7. The lever is extended, as indicated at 10, beyond the bar or rod 7 to afford an operating handle whereby the requisite endwise movement to the bar or rod 7 may be accomplished with convenience and facility. 95 The handle or lever portion 10 is provided with the spring-controlled latch 11 adapted to coact with the segmental rack 12 carried by the bar or member 1 whereby it will be seen that the cams 5 may be positively 100 locked and maintained in their different adjustments.

105 The member 1 has suitably anchored, as at 12, and adjacent each extremity a flexible member 14 (herein shown as a linked chain) which may be of any preferred length and which has its outer or free extremity terminating in an engaging member 15 adapted to coöperate with a stretcher or any other object as the necessities of practice may dictate.

110 From the foregoing description of my

improvement, it is thought to be obvious that a wire clamp constructed in accordance with my invention is of an extremely simple and comparatively inexpensive nature and is particularly well adapted for use by reason of the convenience and facility with which it may be manipulated, and it will also be obvious that my invention is susceptible of some change and modification without material departure from the principles and spirit thereof, and for this reason I do not wish to be understood as limiting myself to the precise arrangement and formation of the several parts herein shown in carrying out my invention in practice.

I claim:

A device of the character described comprising an elongated member, a plurality of spaced plates secured thereto, said plates

being substantially L-shape in cross section, 20 cam members pivotally mounted with relation to said plates, each of said cam members being provided with an extension, a bar pivotally engaged with the extensions of the cams whereby said cams may be 25 caused to move in unison, a lever member pivotally engaged with the elongated member and the bar, a segmental rack carried by the elongated member overlying the bar, and a latch carried by the lever engageable 30 with the rack for locking the bar in its different positions.

In testimony whereof I hereunto affix my signature in the presence of two witnesses.

JOHN ERVIN PECKENPAUGH.
